UNITED STATES PATENT OFFICE

VANCE S. FIRESTONE AND DELBERT SWARD, OF FREEPORT, ILLINOIS, ASSIGNEES TO
ARCADE MANUFACTURING COMPANY, OF FREEPORT, ILLINOIS, A CORPORATION OF
ILLINOIS

LATCH

Application filed November 12, 1928. Serial No. 318,765.

Our invention relates more particularly to latches for refrigerator doors.

One of our objects is to provide a construction of latch which will operate automatically, without the use of springs which are objectionable, to lock the door by the mere act of closing the door and by which the more forcibly the door is swung toward closed position, the tighter the door will close.

10 Another object is to provide a construction operating as above stated and which shall comprise a single handle member for the unlatching and opening of the door.

15 Another object is to provide a latch construction comprising leverage means operative to effect the initial movement of the door towards open position to the end that such movement of the door may be effected with the exertion of relatively slight force even though the door be in tightly closed condition.

20 Another object is to provide a construction of latch device of the type which automatically latches the door upon the act of swinging the door to closed position which will be more positive in its operation than devices as hitherto constructed; and other objects as will be manifest from the following description.

30 Referring to the accompanying drawings: Figure 1 is a broken face view of the front of a refrigerator structure containing an opening equipped with a door hinged thereto and provided with latch means for the door in accordance with our invention, the door being shown in tightly closed condition.

35 Figure 2 is an edge view of the structure of Fig. 1 showing the door in partially open condition.

40 Figure 3 is a side view of the keeper forming one of the parts of the latch mechanism, this view showing the side of the latch opposite that shown in Fig. 2.

45 Figure 4 is a plan sectional view taken at the irregular line 4—4 on Fig. 1 and viewed in the direction of the arrows; and

50 Figure 5, a similar view showing the positions occupied by the parts of the latch

mechanism following the initial opening of the door.

Referring to the drawings, 6 represents a refrigerator structure containing an opening 7 in its wall, and 8 a door forming a closure for said opening and hinged to the structure 6 as represented at 9 and in accordance with common practice.

55 The particular illustrated embodiment of our invention comprises a keeper 10 for attachment to the outer face of the structure 6 adjacent the side of the opening 7 opposite that at which the door 8 is hinged, this keeper comprising a plate 11 at which it is attached to the structure 6, as by screws 12, and a forwardly projecting portion 13 having a depending extension 14 presenting at its forward extremity a rearwardly and downwardly curved surface 15 and, to the rear of said surface, an upwardly and rearwardly inclined cam-forming, or wedge, surface 16.

60 The latch mechanism also comprises a latch-lever 17 pivotally connected between its ends at 18 to a plate 19 attached to the face of the door 8 adjacent the keeper 10, by screws 20. The lever 17 presents the handle portion 21 which is deflected outwardly to extend in spaced relation to the door 8 as shown in Fig. 4 and by which the unlatching of the door and the opening of the 65 latter is effected. The pivoting of the lever 17 is on a substantially horizontal axis 75 whereby this lever swings in a plane substantially parallel with the face of the door 8 and the end thereof opposite the handle portion 21 and represented at 22 is provided for latching with the keeper 13.

70 The latch mechanism also comprises a dog, 75 represented at 23, and pivoted on a substantially vertical pin 24 mounted in vertically spaced lugs 25 and 26 on the plate 19, the dog 23 extending into the space between these lugs and thus adapted to rock in a substantially horizontal plane.

75 The dog 23 is of general bell crank form as shown providing the angularly disposed arms 27 and 28 provided for engagement, respectively, with the top of the lever 17 to the right, in Figs. 1 and 4, of the pivot 190

of this lever and with an abutment 29 formed rigidly on the keeper 10.

The arrangement of the parts shown and described is such, as shown, that assuming the door to be open, in which position of the door the unbalanced lever 17 assumes substantially horizontal position, its left-hand end abutting the underside of a depending stop-lug 30 on the dog 23, the swinging of the door toward closed position causes the end portion 22 of lever 17 to ride against the cam-surface 15 of the keeper thereby causing the lever 17 to be rotated in counterclockwise direction in Fig. 1, to a position in which it clears the lower extremity of the keeper portion 14. As the door nears closing position the arm 27 of dog 23 engages the abutment 29 thereby rotating the dog in counterclockwise direction in Fig. 4 and by the engagement of its arm portion 28 with the upper surface of the portion 21 of lever 17, forcibly rotates this lever in clockwise direction in Fig. 1 which causes the lever-portion 22 to travel up the inclined surface 16 of the keeper and firmly force the door inwardly to closed position shown in Fig. 4, it being understood from the foregoing that the greater the force applied by the operator in closing the door the more tightly the parts of the latch mechanism interengage for forcing the door to closed, latched, condition.

To open the door the operator grasps the handle portion 21 of lever 17 and rotates this lever in counterclockwise direction in Fig. 1 for downwardly swinging the portion 22 of this lever out of interlocking engagement with the keeper. During the movement of the lever as stated, the latter engages the arm 28 of dog 23 thereby rotating the latter in clockwise direction in Figs. 4 and 5 and engaging the arm 27 of this dog with the stop-abutment 29 whereby continued rotation of the lever 17 as stated results in the initial opening, or cracking, of the door as shown in Fig. 5, in which position the lever 17 is entirely clear of the keeper and the operator by merely pulling outwardly on the lever swings the door from the initial open position to the final open position desired.

While we have illustrated and described a particular construction embodying our invention, we do not wish to be understood as intending to limit it thereto as the same may be variously modified and altered without departing from the spirit of our invention.

What we claim as new, and desire to secure by Letters Patent, is:

1. A latch mechanism for a door adapted to close an opening in a casing, said latch mechanism comprising a keeper on said casing, a lever pivoted on said door for interlocking with said keeper, and a dog of general bell crank form pivoted on said door and so positioned that, in the closing of the door, one arm of said dog engages a stationary

part of the structure and its other arm presses against said lever and rocks the latter into tight engagement with said keeper.

2. A latch mechanism for a door adapted to close an opening in a casing, said latch mechanism comprising a keeper on said casing, a lever for interlocking with said keeper and pivoted on said door to swing in a plane substantially parallel with the face of the door, and a dog pivoted on said door and so positioned that, in the closing of the door, one portion of said dog engages a stationary part of the structure and another part thereof presses against said lever and rocks the latter into tight engagement with said keeper.

3. A latch mechanism for a door adapted to close an opening in a casing, said latch mechanism comprising a member on said casing and having a rearwardly and upwardly inclined rear surface, a lever for interlocking with said keeper at said surface and pivoted to said door to swing in a plane substantially parallel with the face of the door, said lever normally extending substantially horizontally and said keeper being provided with an abutment, and a dog pivoted on said door on an axis extending at an angle to the axis about which said lever rocks, said dog being of general bell crank form and so positioned that, in the closing of the door, one arm of said dog engages said abutment and its other arm presses against said lever and rocks the latter into tight engagement with said keeper.
